CLAIM

The ornamental design for a truck cab, as shown and described.

DESCRIPTION

FIG. 1 is an isometric view of the truck cab showing our new design.

FIG. 2 is a side elevational view thereof.

FIG. 3 is a top plan view thereof.

FIG. 4 is a front elevational view thereof.

FIG. 5 is a rear elevational view thereof.

FIG. 6 is a bottom plan view thereof.

The broken lines in the drawing are for illustrative purposes only and form no part of the claimed design.
